UNITED STATES PATENT OFFICE.

DUFFY L. CAMPBELL, OF ROSEMARY, NORTH CAROLINA.

COMBINATION-PADLOCK.

941,128.

Specification of Letters Patent. Patented Nov. 23, 1909.

Application filed February 8, 1909. Serial No. 476,747.

To all whom it may concern:

Be it known that I, DUFFY L. CAMPBELL, a citizen of the United States, residing at Rosemary, in the county of Halifax, State 5 of North Carolina, have invented certain new and useful Improvements in Combination-Padlocks; and I do hereby declare the following to be a full, clear, and exact description of the invention, such as will enable others skilled in the art to which it appertains to make and use the same.

This invention relates to combination padlocks, and has for one of its objects to simplify and improve the construction and increase 15 the efficiency and utility of devices of this character.

With this and other objects in view the invention consists in certain novel features of construction as hereafter shown and described and then specifically pointed out in the claims, and in the drawings illustrative of the preferred embodiment of the invention, Figure 1 is a side elevation of the improved device. Fig. 2 is an edge view of 25 the same. Fig. 3 is a view of the lock with the cover detached and with the locking disks in position therein. Fig. 4 is a section on the line 4—4 of Fig. 3.

The improved device comprises a casing 30 formed in two parts, the body portion 10 which contains the locking mechanism and the cover 11 detachably secured to the body by one or more rivets or similar fastening devices 12, the casing and the cover portion 35 being of ordinary form.

Swinging at 13 from the casing 10 is a shackle 14, the shackle having a notch 15 at its free end, as shown. Mounted to slide through keepers 16—17 within the body 10 40 is a bolt 18 with one end inclined as at 19 to engage in the notch 15, and with a spring 20 operating to maintain the bolt yieldably in engagement with the shackle.

Slidable through keepers 21 is a presser 45 member 22 having a projection 23 engaging against the inner end of the shackle 14 when the latter is in its inward position, the member 22 maintained yieldably in its outward position by a spring 24. By this means it 50 will be obvious that when the end 25 of the shackle 14 is released, the bolt 18 and the member 22 will be maintained in their projected positions by their springs 20—24 and

in position to receive the shackle 14 when the latter is inserted into the body of the 55 casing. When the shackle is thus inserted, its inclined terminal 25 will displace the bolt 18 and the portion 23 of the member 22 against the action of the springs 20—24, and when the notch 15 passes the inclined 60 end 19 of the bolt, the latter will be forced by its spring 20 into engagement with the notch and thus lock the shackle to the casing. When the bolt 18 is released by the unlocking mechanism, hereafter described, 65 the spring 24 will exert its force to eject the shackle from the casing.

Projecting through the cover member 11 at spaced intervals are two stub shafts 26—27, the shafts having knobs 28—29 at 70 their outer ends and carrying disks 30—31 at their inner ends within the casing. The disk 30 is provided with a notch 32 in its rim while the disk 31 is provided with a similar notch 33 in its rim. Arranged within the 75 body 10 of the casing are two guides 34—35 spaced apart, and slidably operating through these guides are pins 36—37, the pins connected by a bar 38. The bar 38 is provided with depending studs 39—40 adapted to 80 enter the notches 32—33, when the disks 30—31 are arranged in certain predetermined positions, as hereafter explained.

Connected to the bar 38 is a rod 41 extending through a notch 42 in the bottom of 85 the body portion 10, the rod having a knob 43 externally of the casing. Surrounding the rod 41 between the rod 38 and the body portion of the casing is a spring 44 operating to maintain the bar 38 and its studs 90 39—40 yieldably in their upward positions.

Pivoted at 45 in the body 10 of the casing is a bell crank lever 46, one arm of the lever extended for contact with a stud 47 extending from the bolt 18, while the other arm 95 of the bell crank is connected by a rod 48 to the rod 41. By this means it will be obvious that when the rod 41 is moved downwardly by a pulling force applied to the knob 43, the bolt 18 will be moved laterally 100 to release the shackle 14.

The disks 30—31 are provided respectively with tension springs or brakes 49—50, to prevent them from moving too freely.

Formed upon the outer face of the cover 105 11 are semiglobular projections 51—52 sur-

rounding the stub shafts 26-27, and provided with radial graduations 53-54 with numerals or other characters between the graduations, as shown.

- 5 The knobs 28-29 are provided respectively with radially extending fingers 55-56 adapted to operate over the graduations 53-54, the fingers being preferably integral with the knob, as shown in Fig. 4. The knobs 10 28-29 are adjustably connected to their respective stub shafts, so that they may be adjusted rotatively relative to the graduations, and thus alternate their positions, to alter the "combination" to any required 15 extent.

The stub shafts 26-27 are provided respectively with heads 57-58, and these heads are provided with openings to receive screws 59-60 by which the knobs may be 20 adjustably coupled to the stub shafts, as shown.

It will be understood that in order to enable the lock to be opened, it will be necessary to so adjust the disks 30-31 as to 25 locate the notches 32-33 opposite the studs 39-40 of the bar 38, to enable the bar to be moved by a pulling force applied to the knob 43, this movement, as above described, causing the operation of the bolt 18. It 30 will be understood, however, that this movement of the bar 38 cannot be accomplished unless the disks 30-31 are located as above described, and by adjusting the knobs and 35 fingers 55-56 relative to the graduations 53-54, it will be obvious that the graduations and fingers may be so located as to cause the notches 32-33 of the disks to be 40 adjusted in position to receive the studs 39-40, when a pulling force is applied to the knob 43.

It will be obvious that a very large variety of combinations may be devised to render the opening of the lock practically impossible by any person not in possession 45 of the selected combination.

What is claimed, is:—

1. In a combination padlock, spaced guides, a bar having pins slidably engaging said guides and with a plurality of projecting studs, a plurality of disks mounted for rotation, each disk being provided with a peripheral notch adapted to receive one of said studs when the disks are arranged in predetermined positions, a rod, spring 50 supported and engaging said bar and maintaining the same yieldably against said guides, a shackle mounted to swing at one end, a slidable bolt adapted to engage the free end of said shackle, connecting means 55 between said slidable bolt and the rod, and means for rotating said disks.

2. In a combination padlock, an inclosing casing having a detachable cover, spaced guides within said casing a bar having pins

slidably engaging said guides and provided with spaced studs, a plurality of disks mounted for rotation upon said cover, each disk being provided with a peripheral notch adapted to receive one of said studs when the disks are arranged in predetermined positions, a shackle mounted to swing at one end upon said casing, a bolt arranged to slide within said casing and adapted to engage the free end of said shackle, connecting means between said slidable bolt and the bar, means for rotating said disks, and means for actuating said bar and the bolt connected therewith.

3. In a combination padlock, an inclosing casing having a detachable cover, spaced guides within said casing, a bar having pins arranged to slide within said guides and having spaced studs, stub shafts mounted for rotation through said cover, a disk carried by each stub shaft and each provided with a peripheral notch adapted to receive one of said studs when the disks are arranged in predetermined positions, a shackle mounted to swing at one end upon said casing, a bolt arranged to slide within said casing and adapted to be engaged by the free end of said shackle, connecting means between said slidable bolt and the bar, radially arranged graduations upon said cover, a turning knob upon each of said stub shafts, radial fingers associated with each of said shafts, and means for adjusting said fingers and knobs relative to said stub shafts.

4. In a combination padlock, an inclosing casing having a detachable cover, guides spaced apart within said casing and intermediate the ends, a bar having lateral pins slidably engaging through said intermediate guides and having spaced studs, stub shafts carried by said cover, disks carried by said shafts and each provided with a radial notch adapted to receive one of said studs when the disks are arranged in predetermined positions, a shackle mounted to swing at one end, keepers spaced apart within said casing near the shackle, a bolt slidably through said keepers and adapted to engage the shackle, means for actuating said bolt, connecting means between said bar and bolt actuating means, means for rotating said disks, and means for actuating said bar and the bolt connected therewith.

5. In a combination padlock, an inclosing casing having a detachable cover, guides spaced apart within said casing and intermediate the ends, a bar having lateral pins slidably engaging through said intermediate guides and having spaced studs, stub shafts carried by said cover disks carried by said shafts and each provided with a radial notch adapted to receive one of said studs when the disks are arranged in predeter-

mined positions, a shackle mounted to swing at one end, keepers spaced apart within said casing near the shackle, a bolt slidable through said keepers and adapted to engage the shackle, means for actuating said bolt, connecting means between said bar and bolt actuating means, a rod connected to said bar and extending through said casing,

and a spring operating to maintain said bar yieldably in its inward position. 10

In testimony whereof, I affix my signature, in presence of two witnesses.

DUFFY L. CAMPBELL.
